UNITED STATES PATENT OFFICE.

GEORGE G. FREILINGHUYSEN, OF NEWARK, NEW JERSEY.

CAN-COOLING APPARATUS.

Application filed July 9, 1925. Serial No. 42,614.

This invention relates to a novel can cooling apparatus providing reliable and effective means for thoroughly and adequately cooling sealed cans, thereby to place the 5 contents of the can at a proper temperature to prevent fermentation.

In the operation of canning liquids, and articles to be sealed partly or wholly in liquids or juices, that process ordinarily involves raising the temperature of the contents of the can to a sterilizing heat of approximately 135° F., the material thus heated being introduced into the can by a filling machine, from which the filled can 10 passes to a capping machine wherein the cap or can top is hermetically sealed. At this point in the canning process the can and its contents are quite warm, and unless quickly and thoroughly cooled are subject 15 to and liable to fermentation, resulting frequently in spoiling the product, and causing bulging of the can heads which is an indication of fermentation in the can.

By the present invention a prompt and 20 satisfactory cooling of the can and its contents is assured. To that end the invention provides an apparatus including instrumentalities which provide for receiving the sealed cans from the capping machine in substantial quantities so that a large production of sealed cans can be handled at one operation to provide for fully cooling the same and their contents.

The invention also has for a principal 25 object the provision of means whereby the cans are given a rolling, as well as a rocking motion, thus affording an opportunity for all portions of the can contents to come in contact with the cool metal. This will effect 30 a cooling of the can contents throughout, thereby reducing the temperature and properly completing the sterilization thereof.

The fundamental features of the invention are necessarily susceptible of a wide range 35 of structural modification without departing from the spirit or scope of the invention but a preferred and practical embodiment thereof is shown in the accompanying drawings, in which:

Figure 1 is a diagrammatic plan view 40 showing the general lay-out of the instrumentalities constituting the present apparatus.

Figure 2 is a vertical central horizontal

sectional view of the cooling tank, omitting 55 the feeding and delivery mechanism located respectively at opposite ends thereof.

Figure 3 is a top plan view of the feeding mechanism at the can receiving end of the 60 cooling tank.

Figure 4 is a side view of the said can feeding mechanism.

Figure 5 is a vertical cross-sectional view 65 of the can feeding mechanism on the line 7—7 of Figure 4.

Figure 6 is a transverse sectional view 70 of the can feeding mechanism on the line 8—8 of Figure 4.

Figures 7 and 8 are detail plan and sectional views respectively of the can feeding 75 device for arranging the cans in single file order on the feeder belt as they are received from the can capping machine.

Similar reference characters designate corresponding parts throughout the several figures of the drawings.

In carrying forward the invention provision is made in the apparatus for handling a large number of sealed cans whereby factory production can be maintained in the 80 filling and capping of the cans, simultaneously with an effective cooling thereof by means of the present apparatus. To that end the apparatus includes a capacious cooling tank designated generally by the reference character 1. This tank may be constructed in any suitable manner, but preferably is a relatively long rectangular structure essentially consisting of the bottom 2 and the side and end walls 3 and 4 respectively. 85 The said tank is open at the top and has suitable piping connections 5 therewith whereby cool water, at a proper temperature, may be maintained at the proper level therein, and preferably kept in circulation so that as the 90 cans are propelled or carried through the water they will be subject to the cooling action thereof.

Operating through the cooling tank 1 is a can propelling means which provides for 100 propelling a number of cans at a time along a tank floor so that they may be effectively cooled. Preferably these can propelling means consist of an endless carrier consisting of the endless chains 6 to which are 105 connected in any suitable manner, as at 7, the transversely arranged and spaced propeller blades 8 which are arranged on the

2 outside of the chains, and are carried thereby through the bottom portion of the tank longitudinally thereof in the direction indicated by the arrow in Figure 2. The endless chains 6 carrying the propeller blades 8 operate over the sprocket wheels 9—9 and 10—10 located in pairs respectively at the opposite end portions of the tank and carried on the conveyor shafts 11 and 12, one of which shafts is preferably mounted in sliding bearing boxes 13 associated with take-up screws 14 or equivalent devices which provides for taking up slack in the conveyor and maintaining it at a proper operating tension. Power may be applied to the endless carrier or can propelling means in any suitable manner, but this may be advantageously accomplished by providing the shaft 12 at one end of the machine with a worm wheel 15 engaged by a worm pinion 16 on a driving shaft 17 having a worm gear connection 18 with an electrical motor 19, thereby completing an electric drive for the conveyor.

25 At the receiving end of the cooling tank the cans are introduced into the same over a receiving table 21, and guided thereby into the space between a pair of the propeller blades 8. The inner end of the receiving table 21 connects with a downwardly and forwardly inclining guide apron 22 which preferably is struck on the arc of the circle of the sprocket wheel 9 so as to guide the cans which lie between every pair of the propeller blades 8 onto the bottom portion of the cooling tank. To prevent the possibility of the cans as delivered from the receiving table 21 entering between the sprockets 9 a guard plate or bar 23 is arranged 30 inside of the circle of the propeller blades advancing downwardly in front of the table 21, said guard plate or bar being conveniently carried by supporting arms or brackets 24 suitably fastened as at 25 to the side walls of the tank 1, and provided with notches 26 detachably taking over the conveyor shaft 11 at one end of the tank.

50 A group of the sealed or capped cans, as for example, five cans, are fed to the receiving table 21 over an inclined feeding chute 27 leading off laterally from a traveling feeder 28 preferably arranged beyond and at right angles to the receiving end of the cooling tank. The feeder 28 preferably consists of an endless belt arranged over the oppositely located belt rollers 29 and 30 carried upon the shafts 31 and 32 respectively which are mounted in suitable bearings, and one of which shafts, for example, shaft 32, has a worm drive 33 or equivalent connection with the operating motor 34. The upper run of the belt 28 extends over a fixed feed table 28^a which supports the said run of the belt and the cans carried thereby, 55 and the capped or sealed cans are fed to

one end of the belt 28, in suitable order and in proper position, by means of a can guiding device which serves to direct the cans from the capping machine and assemble them in single file order on the receiving end portion of the upper run of the belt 28.

60 A preferable form of can guiding device having these desirable functions is shown in the accompanying drawings, and consists of an inclined flanged slideway or apron 35 75 which receives the cans upright from the delivery table 36 of the can capping machine. This slideway or apron 35 is preferably of a downwardly convergent form, serving to permit the cans to slide downward in an upright position until the lower end portion of the can encounters a fixed trip bar or shoulder 37 arranged transversely across the lower open end portion of the slideway or apron 35 and serving to trip the upright can, 80 causing the same to fall to a horizontal position on top of the upper run of the moving belt 28. Beyond the said trip bar or shoulder 37 there is arranged over and along one edge portion of the belt 28 a curved 85 guiding wall 38 against which one end of the upset can will frictionally engage while the belt 28 moving in the direction shown in Figures 7 and 8 draws the can into substantially the longitudinal plane of the belt 28. 90 In this way the cans are brought into single file order on the top run of the belt 28 and are advanced by the latter to a kick-off station where a group of the cans, for example five, are shoved or kicked onto the inclined 100 feeding chute 27 and from thence on to the receiving table 21 at the receiving end of the cooling tank.

95 The means for automatically throwing or kicking a number of the cans, as for example 165 a group of five, off of the traveling feeding table or belt 28 may consist of any suitable instrumentalities having the capacity for doing that work but a preferable form of construction is shown in detail in Figs. 5 110 and 6 of the drawings. Referring particularly to these figures of the drawings as well as to Figs. 3 and 4 it will be observed that the said throw-off device of the can feeding mechanism includes a push bar 39 115 arranged at one side of the fixed table 28^a and the belt 28 thereover at a point parallel to and above the same, that is, in a position to engage against one side of the plurality of cans to be fed to the end of the cooling 120 tank. This push bar may be of any desired form, as shown in the drawings, and of any material though preferably being of wood and the same is carried upon the upper ends of a series of supporting arms or brackets 40 125 which at their lower end are suitably mounted on or connected to a rock shaft 41 journaled in suitable bearings 42 beneath the fixed feed table 28^a. This rock shaft also carries a bracket or brackets 43 supporting 130

at one end a stop bar 44 extending longitudinally of the fixed feed table 28^a and normally projecting upwardly through a clearance slot 45 therein so that the upper edge 5 of the stop bar will normally project above the top of the table 28^a in the path of the cans on the delivering end of the belt 28 so as to prevent them from prematurely rolling off onto the feeding chute 27 before the 10 push bar 39 comes into action. A retracting spring 46 connected at one end to a fixed point of attachment as at 47 and at its other end as at 48 to an arm 49 on the rock shaft 41 serves to normally hold said rock shaft 15 in a position to normally hold the push bar 39 in an inoperative position and the stop bar 44 in an operating position. At a convenient point thereon the rock shaft 41 has fitted thereto a cam projection 50 presenting 20 at one side an abrupt engaging shoulder 51 adapted to be engaged by the end of an actuating detent 52, which end of said detent is bevelled at one side as at 53.

The detent 53 is movably mounted in a 25 slide bar 54 which is arranged to slide horizontally beneath the table 28^a in suitable aligned guides 55 and the lower end portion of the detent 52 has associated therewith a supporting spring 56 held in a suitable 30 bracket 57 at the underside of the slide 54 and serving to normally and yieldingly project the upper shouldered and bevelled end of the detent above the top surface of the slide 54. Accordingly, by reason of this 35 construction it will be apparent that when the slide 54 is moved in one direction the flat or shouldered upper end thereof will engage against the shoulder 51 of the cam projection 50 thereby rocking the shaft 41 in a 40 direction that will snap the push bar 39 forwardly against the cans on the delivering end of the belt 28 and shove or kick said cans onto the feeding chute 27 in a manner and at a time which will be more fully referred to later on. 45

A feature of practical importance in connection with the throw-off device or kicker of the can feeding mechanism is a detaining device which is so timed in relation to the 50 operation of the throw-off device or kicker as to temporarily detain or hold back the feeding of the cans from the delivery end of the feeding belt 28 until the throw-off device or kicker is actuated to shove the group of cans onto the inclined feeding chute 27 leading to the feeding-in end of the cooling tank. This detaining device in its preferable construction includes a brake shoe 58 arranged in a location slightly in advance of the location of the push bar 39, said brake shoe being mounted on an upstanding brake arm 59, the lower end of which brake arm is fitted to a rock shaft 60 mounted in suitable bearings 61 at the underside of the fixed feed table 28^a. 55 The rock shaft 60 for the detaining or

braking device also has fitted thereto a rocker arm 62 having a shouldered flat tip 63 adapted to be engaged by the upper end of an actuating detent 64 having a bevelled face 65, the said bevelled upper end of the 70 detent 64 being normally projected above the upper side of the slide 54 and adapted to engage in both directions of movement of said slide with the shouldered flat tip 63 of the rocker arm 62. The said actuating detent 75 64 for the brake shoe rock shaft is preferably in the form of a pivotal member which is pivoted intermediate its ends as at 66 within a recess 67 in the slide bar 54 and the lower end of the pivotal member has connected thereto as at 68 one end of a coil spring 69 which normally acts to hold the upper part of the detent against one wall of the recess 67 so that as the slide bar 54 moves in the direction of the arrow shown 80 in Figure 6 the pivoted end 65 of the detent will serve to lift the rocker arm 62, rocking shaft 60 in the direction which moves the brake shoe 58 into frictional detaining engagement with the can following the last 85 can of the group which has been carried alongside of the push bar 39, and said brake shoe will be held in said operative position while the upper flat end of the detent 64 dwells on the flat part of the tip 63 of the 90 rocker arm 62. When the upper end of the detent 64 passes off of the flat part of said tip 63 the said arm 62 will rock as the brake shoe is eased from the can which it engages by the action of the spring 70. 100

It will be observed, in connection with the detaining device or brake for arresting the feed of cans on the belt 28 while the throw-off device or kicker is acting, that the table 28^a is formed with a runway along that part 105 of the belt where the detaining device or brake is located. This runway is preferably formed by the fixed table 28^a itself and the guard rails 71 which are mounted at the upper side of the table 28^a and at opposite side edges thereof and are provided with bevelled inner sides 72 against which the cans may freely slide and engage, and when the brake shoe 58 is pressed against a can that can will in turn be pressed against the 110 opposite guard rail 71 so that it will be firmly held between that rail and the brake shoe until the latter eases off and permits the belt 28 to again take up its feed of cans in single file to their delivery position at one 115 side of the push bar 39. 120

Now, it will also be observed by reference to the details of the mechanism shown in Figure 6 of the drawings that upon the movement of the slide bar 54 in the direction indicated by the arrow that the actuating detent 52 comes against the shoulder of the cam projection 50 of the rock shaft 41 and at the same time the detent 64 has raised the 125 rocker arm 62 and holds it in that position 130

for a period of time sufficient to hold back the feeding of the cans while the detent 52 operates the rock shaft 41 and the push bar 39 thereby to discharge a group of the cans onto the chute 27 and from thence to the receiving table 21 and between the propeller blades in the cooling tank. In these operations the slide 54 may be reciprocated in any suitable manner, as for instance, by the pitman 73 pivotally connected at one end as at 74 to the slide 54 and at its other end to the wrist pin 75 on the crank wheel 76 mounted on its shaft 77 which may be conveniently driven by the chain or equivalent belt 78 driven from a sprocket or equivalent wheel 79 carried on the endless carrier shaft 11 associated with the cooling tank; the take-up device 13—14 previously referred to assisting also to maintain a proper take-up or tension on the chain or belt 78. It will also be noted that the adjacent one extreme end of the traveling feeding belt 28 there is arranged over said belt a stationary stop 80 of any suitable form to act as a limiting stop to arrest the movement of the group of cans which have been carried by the belt 28 to a position at one side of the push bar 39 of the throw-off or kicker device.

It has been previously pointed out that the group of cans delivered by the can feeding mechanism into the receiving end of the cooling tank are rolled along a floor or bottom of the tank, thereby submitting the cans and their contents to a very thorough and extended cooling and as the cans reach the delivery end of the tank they are propelled upwardly by the blades 8 of the endless carrier over a terminal guide plate or member 81 and onto a delivery table 82, the said delivery table being preferably inclined so that the cans will roll therefrom to any suitable carrying devices 83 not claimed herein.

From the foregoing it is thought that the construction, operation and many advantages of the herein described invention will now be apparent without further description and it will of course be understood that changes in the form, proportion and minor details of construction may be resorted to without departing from the spirit of the invention and scope of the appended claims.

I claim:

1. A can handling apparatus including a can feeding mechanism comprising a feeding belt arranged at or adjacent a feeding position, a can guiding device positioned at an angle to said belt and having means for directing cans while in an upright position in a direction toward the belt, means for overturning the individual cans from the upright to a horizontal position, and means for turning the upset cans onto the feeding belt longitudinally thereof.

2. A can handling apparatus including a can feeding mechanism comprising a feed-

ing belt disposed beyond a feeding position, a can guiding device over one end of the belt having a slideway positioned at an angle to the belt, for the passage of the sealed cans in upright position, means for tripping the cans onto the belt, means for positioning the tripped cans endwise longitudinally of the belt, and a discharging or kicker device for the cans over the belt.

3. A can handling apparatus including a can feeding mechanism comprising a feeding belt, a can guiding device having a slideway for the sealed cans in upright position, and arranged in a plane at right angles to said belt, means for tripping the cans onto the belt and a guiding wall arranged over the belt and having means for assembling the cans end to end in single file order on the belt, and a discharging or kicker device for the cans over a portion of the belt.

4. A can handling apparatus including a can feeding mechanism comprising a driven belt, a can discharging device consisting of a spring-held rock shaft carrying a push bar and a cam projection and a reciprocating slide carrying an actuating detent for engaging said cam projection.

5. A can handling apparatus including a can feeding device comprising a driven belt, a can discharging device consisting of a spring retracted rock shaft carrying a push bar operating against cans on the belt and a shouldered cam projection on said shaft, a detaining device consisting of a rock shaft carrying a brake shoe for engaging with the can on the belt and also carrying a rocker arm, and a reciprocating slide bar carrying separate detents respectively engaging the cam projection on one rock shaft and the rocker arm on the other rock shaft, the action of said detents being so timed that the brake member will engage and detain a can during the movement of the push bar to discharge cans from the belt.

6. A can handling apparatus including a can feeding mechanism comprising a feeding belt for carrying the cans in single file order, and inclined chute on which the cans in a semi-vertical position slide, means for upsetting the cans from the chute onto the belt, means for bringing a group of the horizontal cans on the belt to an assembled position end to end and means for rolling the assembled cans off the belt to a desired position.

7. A can handling apparatus including a can guiding device having a gravity slideway for causing the sealed cans to slide downward in a semi-upright position, means for upsetting the sealed cans to horizontal position, means for conveying the horizontal cans to an assembled position end to end and means for rolling the assembled cans to a desired position.

8. A can handling apparatus including

85
